UNITED STATES PATENT OFFICE.

CHARLES A. BAILEY, OF CROMWELL, CONNECTICUT.

TOY PISTOL.

1,308,143.

Specification of Letters Patent.

Patented July 1, 1919.

Application filed February 26, 1919. Serial No. 279,265.

To all whom it may concern:

Be it known that I, CHARLES A. BAILEY, a citizen of the United States, residing in Cromwell, in the county of Middlesex and 5 State of Connecticut, have invented a new and Improved Toy Pistol, of which the following is a specification.

My invention relates to the class of toy pistols designed for exploding "paper caps", 10 and an object of my invention, among others, is to provide a device of this class with simple means for feeding a strip or tape containing such caps disposed lengthwise thereon.

15 One form of device embodying my invention and in the construction and use of which the objects herein set out, as well as others, may be attained, is illustrated in the accompanying drawings, in which—

20 Figure 1 is a view in side elevation of a toy pistol embodying my invention.

Fig. 2 is a top plan view of the same.

Fig. 3 is a view looking at the front end of said pistol.

25 Fig. 4 is a view in side elevation of a portion of my improved pistol illustrating mechanical means for feeding the tape.

In the accompanying drawings the numeral 5 indicates the frame of my improved 30 toy pistol, said frame having a tape chamber 6, preferably open on one side, a barrel extension 7 and a handle 8. An anvil 9 is located at the top of the frame and a hammer 10, pivotally mounted in the frame, and 35 of any desired construction, and operated in any desired manner, is adapted to strike said anvil under the force of a spring connected with the hammer in a manner to throw it forward against the anvil.

40 A guide 11, preferably of curved form, comprises one wall of the chamber 6, said guide being secured at one end to a stud 12 projecting from the frame, the opposite end of said guide being pressed into contact with 45 the face of the anvil. This guide may be constructed of spring metal to effect this purpose. A tape supporting stud 13 projects laterally from the frame at the front end of the chamber 6 and it has a retaining 50 finger 14 projecting at an angle to the main part of the pin as an aid in retaining a roll of tape composed of the paper caps in place.

In the operation of the pistol the finger of the operator is placed on that part of the 55 tape resting on the guide 11 and is moved along the curved part of the guide to move

the tape upwardly to position a cap on the anvil, in this movement of the finger the guide being pressed away from the anvil to free this end of the tape so that it may be 60 moved upwardly. The end of the guide resting against the anvil provides a shield that prevents the fire from an exploding cap on the anvil from communicating to succeeding caps in the tape.

65 In Fig. 4 of the drawings means are shown for mechanically feeding the tape along the guide, in the mechanism shown a slide 15 is mounted for reciprocating movement on the frame, this slide having a retaining finger 16 projecting through a slot 17 in the frame to guide it in its movements, a hammer 18 projecting from the upper end of the slide in position to strike the anvil 9 when the slide is forced forward as by a 75 spring 19.

A feed finger 20 projects from the slide in position to engage the paper tape 21 and move it along the guide 22 when the slide is moved backwardly, the tape being thus fed 80 upwardly to the anvil, and the finger 20 being released from the tape when the slide moves forward. A second retaining finger 23 projects from the slide through an opening 24 having a cocking notch 25, forming a 85 shoulder 26 to receive a cocking shoulder 27 formed at the lower front edge of the slide. In the operation of this part of the device the slide is moved backwardly by pressure upon the trigger 28 until the edge 90 27 engages the shoulder 26 to hold the slide in its rearward position. In this rearward movement the finger 20 engaging the tape presses the spring 22 away from the anvil and moves the tape with the next cap thereon 95 into position to be fired.

In accordance with the provisions of the patent statutes, I have described the principles of my invention, together with the device which I now consider to represent the 100 best embodiment thereof; but I desire to have it understood that the device shown is only illustrative, and that the invention may be carried out by other means.

I claim—

105 1. A toy pistol including a frame having an anvil, means for delivering a blow against said anvil, and a spring guide extending backwardly and curved upwardly and terminating back of said anvil to direct the movement of a tape, whereby force applied to a tape to move it endwise along said guide to

110

feed it to said anvil will release the guide from said anvil.

2. A toy pistol including a frame having an anvil, means for delivering a blow against said anvil, and a resilient curved guide extending backwardly and curved upwardly and having its ends pressed yieldingly into contact with said anvil, said guide being positioned to receive pressure applied to a tape thereon, whereby said pressure will feed the tape along said guide and release the latter from pressure on said anvil.

3. A toy pistol including a frame having an anvil, means for delivering a blow against said anvil, said frame having a chamber, a roll supporting pin projecting from the frame adjacent to said chamber, and a spring guide extending backwardly and curved upwardly and terminating back of said anvil to direct the movement of a tape, whereby force applied to a tape to move it endwise along said guide to feed it to said anvil will release the guide from said anvil.

4. A toy pistol including a frame having an anvil and a chamber open to one side, a

roll supporting pin projecting laterally from the frame and having an angularly disposed end to retain a roll of paper tape on said pin, and a guide to direct the movement of the tape having force applied to move it endwise along said guide to feed it to said anvil.

5. A toy pistol including a frame having an anvil, means for delivering a blow against said anvil, a resilient guide extending backwardly and curved upwardly and terminating back of said anvil to direct the movement of a tape along the guide to said anvil, and a member movably mounted on the frame to engage said tape with pressure to move it along said guide and to force said guide away from said anvil.

6. A toy pistol including a frame having an anvil, a spring guide resting with pressure against said anvil and adapted to receive a tape, said guide being positioned to receive pressure applied to a tape thereon to move it therealong and in a direction to move said guide away from said anvil.

CHARLES A. BAILEY.
